TELEPHONE SECURITY DEVICE

Richard C. Heymann IV, Morristown, N.J.
(68 Haas Road, Millington, N.J. 07946)

Filed Mar. 23, 1971, Ser. No. 127,431

Term of patent 14 years

Int. Cl. D14—03

U.S. Cl. D26—14 A

FIG. 1

FIG. 4

FIG. 3

FIG. 2

FIG. 1 is a rear elevation of a telephone security device showing my new design;

FIG. 2 is a side elevation thereof;

FIG. 3 is a top plan view thereof; and

FIG. 4 is a fragmentary front perspective of the locking member of the security device.

The broken lines representing the telephone are shown for illustrative purposes only.

I claim:

The ornamental design for a telephone security device, as shown and described.
